UNITED STATES PATENT OFFICE

EDWARD F. TERRY, OF PHILLIPSBURG, NEW JERSEY, ASSIGNOR TO INGERSOLL-RAND COMPANY, OF JERSEY CITY, NEW JERSEY, A CORPORATION OF NEW JERSEY

HANDLE FOR ROCK DRILLS

Application filed July 30, 1931. Serial No. 553,939.

This invention relates to rock drills, but more particularly to a handle for rock drills of the drifter type which, when functioning in that capacity, are generally guided and supported in the correct operative position with respect to the work by a cradle or similar device.

In drills of the drifter type the cylinder is equipped with lateral guide ribs which are adapted to slide in guideways in the cradle, and the cradle is equipped with a feeding device, such as a screw, which is suitably held against longitudinal movement with respect to the cradle and is 10 threadedly connected to the rock drill so that, upon rotation of the screw, the rock drill may be advanced or retracted longitudinally of the cradle.

The present invention is more particularly, though not exclusively, intended for use as a means for manually supporting and guiding light weight drifters of which the weight is such that the drifter may be conveniently manipulated by one attendant.

The objects of the invention accordingly are to render a rock drill of the drifter type readily capable for use as a hand held drill, to prevent the transmission of shock and vibrations from the drill to the operator, and to enable the handle to be readily attached to and removed from the drill.

Other objects will be in part obvious and in part pointed out hereinafter.

In the drawings accompanying this specification and forming a part thereof and in which similar reference characters refer to similar parts,

Figure 1 is an elevation partly in section of a handle attached to a rock drill to illustrate a practical application thereof,

Figure 2 is a side elevation of the handle and the rock drill, and

Figures 3 and 4 are transverse views taken through Figure 1 on the lines 3-3 and 4-4 looking in the direction indicated by the arrows.

Referring more particularly to the drawings, A designates generally a rock drill comprising a cylinder B and front and back heads C and D respectively. A front cyl-

inder extension E is interposed between the cylinder and the front head C and is clamped in assembled relationship with respect to the cylinder, as are the heads C and D, by the usual side rods F which extend 55 longitudinally of the drill and on opposite sides thereof. The rear ends of the side rods F are threaded for the accommodation of nuts G whereby the casing elements of the drill may be securely clamped together. 60

On one side of the cylinder B are the guide ribs H which may extend from one extremity of the cylinder to the other, as is customary, for engagement with the guideways of a cradle (not shown) employed as 65 a mounting for the drill.

In accordance with the practice of the invention a casing part, as for instance the front cylinder extension E, is provided with a pair of lateral lugs J having recesses K in 70 the rear sides thereof. At the rear end of the drill and seated upon lugs L of the back head D through which the side rods F extend is seated a plate O having apertures P to receive the side rods F and said plate is 75 securely clamped to the back head D or, more specifically, to the lugs L by the nuts G of the side rods. In the front end of the plate O are recesses Q which are coaxial with the recesses K in the lugs J. 80

Disposed in the recesses K and Q are the ends of rods R which are of uniform diameter throughout and seat with their ends against yieldable buffers S, as for instance rubber, disposed in the bottom of the 85 recesses.

The handle whereby the rock drill may be manipulated and which is generally designated by T comprises a grip portion consisting of outer grip members U and V and an intermediate grip member or spacer W. The members U, V and W are each provided with central apertures X for the accommodation of a bolt Y whereby the grip members are held in axial relationship and are 95 clamped together.

In the assembled position of the handle the grip members occupy a position above the rock drill A and clamped between the ends of the member W and the adjacent ends 100

of the grip members U and V are legs Z which terminate at their lower ends in bosses b having apertures c therein to receive the rods R whereon the said bosses are adapted 5 to slide.

The bosses b may be of substantial length in order to assure ample bearing surface between the said bosses and the rods R. The front and rear ends of the bosses b constitute, in the present instance, seats d and e respectively for springs f and g. The springs f are interposed between the seats d and the lugs J against which they seat with their front ends, while the springs g are 15 interposed between the seats e and the plate O which serves as seats for the rear ends of the springs g.

In addition to the bosses b the handle may be provided with means intended to maintain the legs Z in approximate alignment 20 with the rods R. The means illustrated for this purpose comprises projections h on the opposite ends of the plate O which extend into longitudinal grooves j on the inner surfaces of the legs Z. In order to assure maximum rigidity between the bosses b, said bosses are connected by a bridge or plate k which may be formed integrally therewith.

In practice the handle may be readily 30 attached to the rock drill by first placing the rods R in the aperture c of the bosses. The lower ends of the rods may then be seated in the recesses K and the plate O be disposed on the side rods F and be clamped 35 against the lugs L of the back head by the nuts G, it being of course understood that the springs f and g are first placed in position on the rods before entering the rods in the recesses.

40 By tightening the nuts G to clamp the casing elements of the rock drill securely together, as well as to clamp the plate O in position, the rubber buffers will be compressed and brought to bear firmly against the ends of the rods. During the subsequent 45 operation of the tool and during which time the handle T will of course constantly shift its position relatively to the rods R, the rods R will be held immovable by the buffers 50 S and will therefore not be subjected to the undue wear which would otherwise result were they capable of some degree of movement relatively to the elements wherein they are seated.

55 In the operation of the device, any jars and shocks resulting from the reciprocations of the percussive element of the rock drill or from other causes will be absorbed by the springs f and g instead of being transmitted to the grip portions of the handle.

60 The present invention has been found to be extremely efficient and one of its chief advantages resides in the fact that it may be quickly applied to a preassembled drill 65 of the drifter type for converting such drill

into one of the hand held type and without necessitating the complete disorganization of the drill. This is made possible by the fact that it is necessary only to remove the nuts G. The plate O and the elements constituting the handle structure may then be placed on the drill or removed, whereupon the nuts G may again be threaded on the side rods to clamp the casing elements of the 70 drill together. 75

I claim:

1. In combination, a rock drill having pairs of opposed recesses spaced along the length thereof, a handle, legs on the handle having apertures therein, rods seated with their ends in the recesses and extending through the apertures, springs to oppose the movement of the legs relatively to the rods, and yieldable means in the recesses to serve 80 as abutments for the ends of the rods. 85

2. In combination, a rock drill, means on an intermediate portion of the rock drill having a pair of rearwardly opening recesses therein, means on the rear end of the rock drill having a pair of forwardly opening recesses, rods extending longitudinally of the rock drill and being seated with their ends in the recesses, yieldable buffers in the recesses to serve as abutments for the rods, a handle, legs on the handle and being 90 slideable on the rods, and springs interposed between the said means and the legs to cushion the movement of the handle longitudinally of the rods. 95

3. In combination, a rock drill, means spaced along the length thereof and having pairs of opposed recesses, a handle, legs on the handle having apertures therein, rods seated with their ends in the recesses and extending through the apertures, rubber 100 buffers in the recesses for the ends of the rods, springs acting against the said means and the legs to cushion the movement of the handle longitudinally of the rods, and means to connect the legs adjacent the apertures. 105

In testimony whereof I have signed this specification.

EDWARD F. TERRY.
